PROPORTIONING APPARATUS

Rudy Lowe, Chicago, Ill., assignor to Proportioners, Inc., Providence, R. I., a corporation of Rhode Island

Application March 25, 1933, Serial No. 662,847

20 Claims. (Cl. 210—40)

The invention relates generally to proportioning apparatus and more particularly to such apparatus adapted for feeding a reagent or other treating fluid into a conduit of flowing water or other fluid in quantities which bear a predetermined relation to the quantity of water or other fluid flowing through such conduits.

An important object of the present invention is to provide a new and improved apparatus for injecting reagent or treating fluid into a flowing stream of water or other fluid in a predetermined proportion to the quantity of flowing water.

In the use of apparatus of this character in the field many variable factors must be overcome. For example, the reagent may be relatively volatile so that the suction stroke of the feeding apparatus must be relatively slow. In other cases the viscosity of the treating fluid may be such as to require all movements of the pump to be relatively slow. The pressure of the fluid operating the proportioning apparatus also varies on different installations of the apparatus and this fact makes it necessary to provide many adjustments in the device. Finally, the rate of flow of the major fluid through the conduit varies greatly and the apparatus must in each case be adapted for the particular installation, proper weight being given to the proportion of treating fluid desired and the rate at which such fluid may be moved through the supply system.

In view of these difficulties which must be met in practical installations of apparatus of this character it is another object of the invention to provide such apparatus constructed to provide for a large number of interrelated adjusting operations whereby a workman may install the apparatus so as to operate with maximum efficiency.

Another object of the invention is to provide apparatus of this character constructed to prevent stalling of the flow-responsive actuator when the control valve of the apparatus meets an obstruction, and arranged to apply recurring impacts to the valve to dislodge the obstructing foreign matter and thereby initiate normal operation of the valve.

Another object of the invention is to provide proportioning apparatus of this character embodying means of a simple character whereby the lap and lead of the control valve may be readily adjusted to suit the particular operating conditions encountered and change the rate of the suction and exhaust strokes of the pump and overcome knocking of the reciprocating parts.

Another object is to provide apparatus of this character arranged in a new and improved man-

ner to produce a compact and unitary device adapted to be easily mounted.

Other objects and advantages will become apparent from the following description taken in connection with the accompanying drawings which illustrate the preferred embodiment of the invention and in which:

Fig. 1 is a diagrammatic view of a proportioning apparatus embodying the features of the invention, the apparatus being shown as embodied in a practical installation.

Fig. 2 is a longitudinal sectional view of the proportioning device.

Fig. 3 is a side elevational view of the apparatus shown in Fig. 2, a portion of the gear box shown in vertical section.

In form herein shown the invention is embodied in a proportioning unit 10, adapted for injecting treating fluid from a supply tank 11 into the water or other fluid flowing through a conduit 12. The proportioning apparatus may, as in the present instance, be actuated in direct proportion to the rate of flow of fluid through the conduit 12 by means of a meter 13 interposed in the conduit 12. The meter 13 has an upstanding housing 14 upon the upper end of which the proportioning unit 10 is mounted and supported.

The treating unit 10 consists generally of an impulse motor 15 supported by means of a yoke 16 in spaced aligned relation to a reciprocating pump 17. At one side of the motor 15 a reciprocating valve 18 is mounted to control the motor, and the valve is actuated by the mechanism housed within a gear box 19 which is connected to the yoke 16 and secured on top of the meter housing 14. In the preferred embodiment the pump and motor are arranged in horizontal relation since by this arrangement any leakage of corrosive reagent is drained away from the motor 15 and valve 18 so as to avoid damage thereto.

Considering generally the operation of the device, the mechanism within the gear box 19 is operated by the meter 13 to reciprocate the valve 18 and the valve, in its movements, controls the flow of pressure fluid, preferably taken by means of a pipe 20 from conduit 12. The motor 15 thereby causes periodic actuation of the reciprocating pump 17, the suction stroke of which serves to draw reagent from tank 11 through pipe 21 and a one way valve or stop-cock 22 while the exhaust stroke serves to force the reagent through a one way valve or stop-cock 23 and a pipe 24 into the main conduit 12.

In the form illustrated the yoke 16 consists of a side wall 16a secured by bolts 25 to one side wall 55

19^a of the gear box, and an integral trough shaped bottom wall 16^b, the side and bottom walls 16^a and 16^b, being joined by end walls 16^c. On the opposite end walls 16^c, the motor 15 and the pump 5 17 are secured, the motor 15 consisting of a cylinder 26 within which a piston 27 is reciprocable. The pump 17 comprises a cylinder 28 secured by bolts 29 to the other end wall 16^c and having a piston 30 reciprocable therein.

10 Preferably the motor and pump cylinders are aligned and are operatively associated by a piston rod 31. Such association is, in the present instance, arranged to provide for adjustment of the axial distance between two pistons, thereby enabling the user to adjust the stroke of the pump 15 17. In such adjustment a constant clearance volume is maintained in the pump whereby to adapt the device for lifting volatile reagents from below the level of the pump.

20 To this end the pump piston 30 is of tubular form, having its inner end closed as at 30^a and its open end extending outwardly into the space between the two cylinders to receive the screw threaded end of the piston rod 31. The connection 25 between the rod 31 and the piston 30 is effected by a nut 32 which is threaded on the rod 31 and has an integral bushing 32^a extending into and fixed to the piston 30. A second nut 33 on the rod 31 serves to lock the pistons in the desired 30 adjusted relation.

Between the end walls 16^c of the yoke 16 a scale 35 is mounted so as to be protected by the end walls 16^c and to extend longitudinally parallel to the axis of the piston rod 31. The scale is 35 utilized to indicate the position of the adjustment of the adjustable connection between the pistons 27 and 30, and to facilitate such indication an arm 36 is slidably mounted on the scale 35 so that the arm extends toward the piston rod 31. With this construction the pump piston 30 is 40 completely withdrawn and by matching the arm 36 with the outer end of the piston 30 the length of the piston stroke is indicated on the scale 35.

45 It will be noted that about the inner end of the piston 27 of the pump cylinder, a packing gland 37 is provided, the gland being adapted to be tightened by means of the bolts 29 and their associated nuts 29^a. At the other or closed end of the pump cylinder 28 a test cock 38 is provided 50 together with internally threaded intake and passage ports 39 and 40 respectively. The motor cylinder 26 is also provided with a packing gland 41 about the piston rod 31, bolts 42 being provided for tightening the gland 41.

55 The motor cylinder 26 has pressure fluid ports 43 at its opposite ends which communicate with similar ports 44 opening into the side of a valve chamber 45 of the control valve 18. The valve chamber 45 is preferably cylindrical in form and 60 has a spool type of valve member 46 slidable longitudinally therein. The valve member 46 has four longitudinally spaced annular rings 47 formed thereon so as to provide three spaced annular grooves 48 through which pressure fluid 65 may pass to and from the ports 44. The pressure fluid is conducted from the supply pipe 20 to an annular groove 49 formed in the valve casing 45^a between the two ports 44. Similar exhaust passages are formed by annular grooves 50 in the 70 valve casing 45^a between the ports 44 and the ends of the valve casing. Thus movement of the valve member to its left hand position, as shown in Fig. 75 1, brings one of the valve grooves 48 into communication with one of the ports 44 and one of the exhaust passages 50, while the other one of the

ports 44 communicate through another valve groove 48 with the pressure fluid supply port 49. It will be noted that the end areas of the various rings 47 are balanced so that slight force is required to actuate the valve member 46, and to 5 prevent building up of pressure in the ends of the valve chamber 45, vent passages 51 are formed from the ends of the valve chamber to exhaust ports or channels 50. It will be noted that the valve chamber 45 is made relatively long whereby to permit longitudinal adjustment of the stroke of the valve member.

As will be evident in Fig. 1 of the drawings a piston rod 18^a extends from the valve chamber 45 through a packing gland 52 toward the gear box 19. The outer end of the piston rod 18^a is detachably connected by means of a set screw 53 to a slidable rod 54 which extends through the adjacent wall of the gear box and is screw-threaded at its inner end into a block 55. A similar rod 56 is screw-threaded into the opposite side of the block 55 and extends slidably through the opposite wall of the gear box so as to support the block 55 for movement parallel to the path of movement of the valve 18. In its lower surface the block 55 has a groove extending transversely of the axis of the rods 54 and 56 to receive a roller 57 which is mounted eccentrically of a disk 58. The disk 58 is rotatably supported on a sleeve 59 which is in turn rotatable about a vertical pin (not shown) carried by a plate 60 which rests on the bottom of the gear box 19. Thus in rotation of the disk 58 the rod 54 is reciprocated.

30 Since the valve member 46 may become stalled by foreign matter in the ports 44, a yielding connection is provided between the rod 54 and the piston rod 18^a. To this end the rod 54 is tubular in form and has an expansion spring 54^a fixed therein adjacent to the block 55. Bearing against the end the spring 54^a is a head 31^a formed on 40 the end of the piston rod 18^a, and between the other side of the head 31^a and the outer end of the sleeve-like rod 54 is a second expansion spring 54^b. This spring bears against a collar 54^c which surrounds the piston rod 18^a and is fixed to the 45 rod 54 by the set screw 53.

35 The sleeve 59 and disk 58 are rotated by a suitable gear train which in the present instance consists of intermeshing gears 61 and 62. The gear 61 is fixed on the sleeve 59 while the other 50 gear 62 is carried on a rotatable shaft 63 mounted in and extending vertically through the bottom of the gear box 19. It will be noted that the sleeve 59 and the disk 58 are located eccentrically of the axis of the shaft 63 and that the plate 60 55 is circular and is mounted in a recess 64 for rotation about the axis of the shaft 63. Thus by rotating the plate 60 the disk 58 may be moved toward and away from the valve 18.

60 This construction is utilized to adjust the lap and lead of the valve member 46 and to facilitate this operation an eccentric cam 65 is mounted on a vertical shaft 66 carried by the plate 60 so that the cam engages a radial slot 67 in the plate 60. Thus by rotation of the cam 65 the plate 60 65 may be rotated gradually about the axis of the shaft 63 and an accurate adjustment of the valve 18 effected. To lock the cam in adjusted position a nut 68 is threaded on the shaft 66 above the cam. By adjusting the lap and lead of the valve 46 the speed of the suction or exhaust strokes of the pump may be varied to meet the conditions imposed by the particular reagent to be pumped. Knocking of the reciprocating parts may also be eliminated through this adjustment. 71

At its lower end the shaft 63 has a pin connector so that it may be readily associated with the driven shaft of the meter 13 or other flow-responsive device. Preferably the shaft 63 extends upwardly through the removable cover-plate 10 of the gear box so as to provide for the mounting and actuation of the counter 11 which records the number of rotations of the shaft 63.

The plate 60 and the gearing mounted thereon are held in place by the cam 65 and may therefore be readily removed from the gear box 19, and by substituting different arrangements of gears in the gear box the relative stroking rate of the pump may be varied. This arrangement is extremely valuable in adjusting the unit in many installations.

It will be apparent from the foregoing description that the treating unit provided by the present invention is compact and unitary in character due to the novel and advantageous arrangement of the elements thereof. It will also be apparent that the simple and accurate adjustment of the control valve enables the operator to overcome knocking of the reciprocating parts, and when taken in connection with the adjustment of the piston stroke, the valve adjusting means enables the operator to adapt any unit to a large variety of operating conditions. The fact that the gear plate 60 and the associated gears may be readily removed and replaced also serves to render the unit effective in many installations which would otherwise require specially built devices.

I claim as my invention:

1. In a proportioning device of the character described, the combination of a pump, a reciprocating fluid pressure operated motor operatively connected to said pump, a reciprocating valve controlling the flow of pressure fluid to said motor, a flow responsive device operable independently of said motor, and an operating connection between said device and said valve for reciprocating said valve, independently of the motor and including means for adjusting the lap and lead of said valve.

2. In a proportioning device of the character described, the combination of a pump, a reciprocating fluid pressure operated motor operatively connected to said pump, a reciprocating valve controlling the flow of pressure fluid to said motor, a rotably mounted shaft, a reciprocating valve operating rod, gear mechanism connecting said shaft with said rod eccentrically of said shaft to reciprocate the rod when said shaft is rotated, and means supporting said gear mechanism for shifting movement about the axis of said shaft whereby to adjust the lap and lead of said valve.

3. Apparatus of the character described comprising a reciprocating motor, a reciprocating pump actuated thereby, a reciprocating valve controlling said motor, a gear box having a rotary driven shaft therein, reduction gearing in said gear box driven from said shaft and having a terminal gear operatively connected to said valve to reciprocate the same when said gear is rotated, and means supporting said gearing to move said terminal gear toward and away from said valve and thereby adjust the lap and lead of the valve.

4. Apparatus of the character described comprising a reciprocating motor, a reciprocating pump actuated thereby, a reciprocating valve controlling said motor, a gear box having a rotary driven shaft therein, reduction gearing in

said gear box driven from said shaft and having a terminal gear operatively connected to said valve to reciprocate the same when said gear is rotated, a plate supporting said gearing and mounted for rotative movement about the axis of said shaft, said terminal gear being eccentrically located with respect to said shaft, and means for imparting finely graduated rotational movement to said plate.

5. In a proportioning unit, the combination of a reciprocating motor, a pump operated thereby, a reciprocating valve controlling said motor, reduction gearing including a terminal gear operatively connected to said valve to reciprocate the same, and means supporting said terminal gear for shifting movement toward and away from said valve.

6. In a proportioning unit, the combination of a reciprocating motor, a pump operated thereby, a reciprocating valve controlling said motor, reduction gearing including a terminal gear operatively connected to said valve to reciprocate the same, a mounting shaft for said terminal gear, means supporting said shaft for shifting movement toward and away from said valve, and means for locking said means in the desired adjusted position.

7. A device of the character described comprising aligned motor and pump cylinders separated longitudinally to provide an appreciable intermediate space, a tubular piston having a closed end located in said pump cylinder and an open end projecting from said pump cylinder into said space, a piston in said motor cylinder having a piston rod projecting axially from said cylinder into said space and into the open end of said tubular piston, means in said space forming a longitudinally adjustable connection between said rod and said tubular piston for adjusting the distance between the remote ends of said pistons, and valve means controlling the flow of motive fluid to said motor cylinder.

8. Apparatus of the character described combining aligned pump and motor cylinders, pistons in said cylinders, a reciprocating valve for controlling the flow of pressure fluid to said motor cylinder, an actuator for reciprocating said valve including means for adjusting the lap and lead of the valve and means connecting said pistons operable to vary the distance therebetween.

9. A device of the character described comprising a reciprocating motor, a reciprocating pump actuated thereby, means operable to adjust the stroke of the pump while maintaining a constant clearance volume therein, a reciprocating valve controlling the motor, replaceable reduction gearing having a connection operable to reciprocate the valve and means for adjusting the lap and lead of the valve.

10. A device of the character described comprising a reciprocating motor, a reciprocating pump actuated thereby, means operable to adjust the stroke of the pump while maintaining a constant clearance volume therein, a reciprocating valve controlling the motor, replaceable positively driven reduction gearing having a terminal connection operable to reciprocate the valve, and means supporting said gearing for shifting said terminal connection substantially along the axis of said valve.

11. A device of the character described comprising a gear box having an open top adapted to be mounted on top of a flow-responsive device, a yoke fixed to and extending longitudinally along one side of said box, a pump cylinder and

5 a motor cylinder horizontally positioned and carried at opposite ends of the yoke in alignment with each other, pistons in said cylinders, means connecting said pistons and extending across said yoke, a valve mounted on the side of said motor cylinder to control the same and adapted for longitudinal sliding movement parallel to said cylinder and toward and away from said gear box, said means in said gear box being operatively connected to said valve for reciprocating the same.

15 the same.

12. In a device of the character described, the combination of a reciprocator pressure fluid operated motor, flow-sensitive device adapted to be interposed in a pipe line and including a rotary element, a rod reciprocated longitudinally by said rotary element, a reciprocator valve controlling the flow of pressure fluid to said motor, and a motion-transmitting connection between said rod and said valve, said connection being yieldable in both directions longitudinally of the rod from a normal centered position.

20

rod from a normal centered position.

13. Apparatus of the character described combining a reciprocatory pressure fluid operated motor, a reciprocatory valve controlling the flow of pressure fluid to said cylinder, an independent power driver element, and means operable by said element to apply yielding force to said valve alternately in opposite directions to reciprocate the valve.

25 of the character described com-

30

35 14. Apparatus of the character described combining a reciprocating pressure fluid operated motor, a reciprocating valve controlling the flow of pressure fluid to said cylinder, a positively driven element actuated independently of said motor for reciprocating said valve and means forming a connection between said element and said valve constructed to yield in either direction from a normal centered relation for a distance exceeding the normal stroke length of the valve.

40

45 15. A device of the character described comprising a reciprocatory motor, a reciprocatory pump actuated thereby, means operable to adjust the pump stroke while maintaining a constant clearance volume therein, a reciprocatory valve controlling said motor, and means for actuating said valve including replaceable gearing for varying the actuation rate of the valve.

50 16. A proportioning device comprising a recip-

rocatory motor, a reciprocatory pump actuated thereby, a rotary flow responsive device adapted to be placed in a pipe line to measure the flow therethrough, a reciprocatory valve controlling said motor, and a connection from said flow responsive device for actuating said valve, said connection including replaceable change gears for varying the relative rate of actuation of said valve.

17. Proportioning apparatus comprising in 10
combination, a reciprocatory pump, a reciproca-
tory pressure fluid operated motor for operating
said pump, a valve for controlling said motor, a
flow responsive device adapted to be connected
in a pipe line to measure the flow therethrough, 15
and an operating connection from said device to
said valve including replaceable change gears
for varying the relative rate of actuation of
said valve.

18. Proportioning apparatus comprising, in combination, a flow responsive device adapted to be positioned in a pipe line to meter the fluid passing therethrough, a supporting structure carried by said device, a reciprocatory fluid motor and a reciprocatory pump operatively interconnected and mounted on said structure, a valve carried by said structure in controlling relation to said motor, and an operating connection between said device and said valve including change gears carried by said structure and mounted for replacement while said pump and motor remain in position on said structure.

19. Apparatus of the character described comprising, in combination, a reciprocating pump, a reciprocating pressure fluid operated motor operatively connected to said pump, means for adjusting the stroke of said pump, a reciprocating valve for controlling said motor and an actuator for said valve including means for adjusting the lap and lead of said valve. 40

justing the lap and lead of said valve.

20. Proportioning apparatus comprising in combination, a reciprocatory pump, a reciprocatory pressure fluid operated motor therefor, a valve for controlling said motor, a flow responsive device adapted to be interposed in a main conduit to meter the flow therein, and an operating connection between said device and said valve including means for varying the relative rate of actuation of said valve.
